EARTH MOVING DEVICE

Ellsworth W. Austin, Cedar Rapids, Iowa, assignor to La Plant-Choate Manufacturing Company, Inc., Cedar Rapids, Iowa, a corporation of Iowa

Application July 25, 1938, Serial No. 221,108

7 Claims. (Cl. 37—144)

One object of my invention is to provide an earth moving device or the like having a main frame which is comparatively simple and also inexpensive from a manufacturing standpoint, yet which secures a number of desirable results.

Another object is to provide a frame for an earth moving device of the type having a blade or other earth handling element for engaging and moving earth upon movement of a tractor on which the blade and frame are mounted, which frame shall permit the blade to be mounted in close relation to the front end of the tractor.

Still another object is to provide a main frame which is so constructed that it is rigid to impact so that a blade carried thereby may be effectively used to push earth or the like ahead of the tractor.

Still a further object is to provide such a main frame having a rugged pivoting means for the blade relative to the frame whereby the lateral inclination of the blade may be readily changed as may be necessary for conforming to the transverse slope of the road or other surface being operated upon by the device.

An additional object is to provide a construction for such a main frame which is particularly adaptable for assembly by welding processes.

With these and other objects in view my invention consists in the construction, arrangement and combination of the various parts of my device, whereby the objects contemplated are attained, as hereinafter more fully set forth, pointed out in my claims, and illustrated in the accompanying drawing, in which:

Figure 1 is a partial side elevation showing the front portion of a Caterpillar type of tractor and a main frame structure embodying my invention mounted thereon.

Figure 2 is a plan view of the main frame and earth moving blade of my device on a reduced scale.

Figure 3 is a horizontal sectional view on the line 3—3 of Figure 1, showing the details of the pivot mounting at the front of my frame, whereby lateral inclination of the blade or other earth moving device is permitted; and

Figure 4 is a vertical cross section on the line 4—4 of Figure 1.

On the accompanying drawing I have introduced the reference character T to indicate generally a tractor. The tractor T is illustrated as having a track frame 10, there being such a frame on each side of the tractor. To the track frame 10 on each side of the tractor is attached a bracket 12.

The main frame of my device is of generally U-shaped form as will be seen from the plan view in Figure 2, wherein is shown only about the front one-third of the frame. The extremities of the U are mounted in the brackets 12 by

means of pivot pins 14. The main frame consists of side portions 16 formed in rectangular box sections as illustrated in Figure 4, preferably by welding two channels together face to face. The frame is continued forwardly and toward the center by angular portions indicated generally at 18. The angular portions 18 are connected at the front by a central portion 20.

The outer ends of the portions 18 are indicated as corners 28, 30, 34 and 40 (see Figure 1) and their inner ends by corners 24, 26, 36 and 38. Each portion 18 comprises a top section 22, a rear section 32, a bottom section 42 and a front section 44. The top section 22 is bounded substantially by the straight lines joining the corners 24, 26, 28 and 30. The rear section 32 is substantially bounded by the lines joining the corners 26, 28, 34 and 36. The bottom section 42 is substantially bounded by the straight lines joining the corners 34, 36, 38 and 40 and the front section 44 may be formed as a plate substantially lying in the surface bounded by the corners 30, 24, 38 and 40. I have shown the upper edge of this plate continued upwardly beyond a line between corners 24 and 30 in the form of a guard plate or apron portion 46. The portion 46 protects the radiator R and other front portions of the tractor T from any dirt or boulders which may spill over the earth moving blade indicated generally as 48.

It will be noted that the structure of the portion 18 which I have described above results in a cross section which varies from one which is horizontally wide and vertically relatively thin at the rear, to one which is horizontally thin and vertically relatively high at the front end.

The front ends of the portions 18 represented by the corners 24, 26, 36 and 38 are connected by the central portion 20 which is similarly transversely thin and vertically high and represented by the same corners 24, 26, 36 and 38. In the drawing I have shown it as including a shallow transverse channel member 50. In actual construction of my frame, the front walls 44 of the portions 18 are continued to form the front wall of the portion 20, the channel 50 being welded thereto to form a box section elongated vertically. The front wall of the portion 20 pointed out above has a continuation of the sections 44 which I have designated as 54. To the front surface of the member 54 I weld ears 56 formed of angle iron and perforated to permit passage of the king pin 60, by which the blade 48 is mounted on the frame. To provide reinforcement of the central portion 20 of the U-frame against the forces exerted through the ears 56 when the device is in operation I weld the angle portions 52 into the portion 20 as indicated in Figure 1.

On each track frame of the tractor T may be mounted a hydraulic cylinder 62 pivotally sup-

ported in a yoke 63 as at 64. The piston rod 66 thereof may be connected by a pivot at 68 to a member such as 70 which is welded to the top and rear section 22 and 32 of the frame portion 18 and more firmly secured thereto by an angle reinforcement 72. By suitable operation of the hydraulic cylinder 62 the whole U-shaped frame assembly together with the blade 48 mounted thereon may be raised or lowered, pivoting on the axis 14. Suitable skids such as 74 may be provided to limit the downward movement of the frame by contact with the ground surface.

In Figure 2 I have shown the blade 48 in a position substantially perpendicular to the longitudinal axis of the tractor T on which the device is mounted. However it is frequently desirable, in the operation of an earth moving machine, to deflect the earth to one side or the other of the machine and this is commonly done by slanting the blade somewhat. In my construction I provide at the outer end of the blade pivot brackets 76 to which are pivotally attached push bars 78 which serve as a thrust connection between the side frame portions 16 and the ends 25 of the blade. The push bars 78 are channel shaped in cross section to partially enclose the side frame 16. The skids 74 are preferably mounted on the push bars 78. Brackets 80 are mounted on the ends of the push bars 78 for connection to the side frame portions 16 and are connected therewith by removable pins 82. The side frame elements have a plurality of sleeve-like perforations 84, 85, 86, 87 and 88 to selectively receive the pins 82.

In Figure 2 the blade 48 is shown adjusted for a bulldozing operation, i. e., for moving earth straight ahead in front of the machine. This adjustment is made by locating the blade in position with the pins 82 in the perforations 87 and 86. For deflecting the earth being moved toward the right the pins would be passed through the brackets 80 and through the perforations 85 and 88. A corresponding arrangement may be made for deflecting the earth toward the left.

In order that the outer ends of the blade 48 guided by the skids 74 on the push bars 78 may conform to moderate variations in the transverse level of the surface being worked upon, it is desirable that the center mounting of the blade to the frame portion 20 should permit some degree of pivoting about a horizontal axis longitudinally of the tractor. To accomplish this desirable result I have devised a particularly suitable means for mounting the blade.

Figure 3 is a detail view showing the novel mounting by which the pivoting above described is made possible. Supported on the frame portion 20 by the king pin 60 is an intermediate mounting assembly composed of the plate 100, the collar 98 and the angle shaped mounting ears 104. The mounting ears have perforations 106 to receive the king pin 60 which passes also through similar perforations in the ears 56 on the main frame. The ears 104 are attached to the plate 100, preferably by welding. The plate 100 has a circular opening 101 centrally located therein, and a collar 98 is located in this opening, and firmly welded to the plate 100.

In Figures 1 and 3 the blade proper is indicated by the numeral 48. 90 designates an additional reenforcing plate used on the rear surface of the blade. At the central portion of the blade in the region of attachment to the main frame an additional reenforcing plate 92 is welded to the blade structure. At the center of this plate is

a circular opening 94 in which a short tube 96 is secured by welding. The blade structure is supported on the intermediate mounting assembly by the tube 96, a part of the blade structure, which passes through the collar 98 of the intermediate mounting assembly and is kept in position therein by angle shaped retainer clips 102 which are welded to the inside of the tube 96 and which extend out over the collar 98, preventing the latter from slipping off the tube 96. It will be seen that the blade structure can be rotated with respect to the intermediate mounting assembly about the common axis of the tube 96 and the collar 98, that axis being coincident in Figure 1 with the section line 3—3. Only a small degree 15 of such rotational freedom is ordinarily necessary. To limit such freedom and to further serve as a retainer in addition to the clips 102 to keep the plate 100 and the plate 92 in close coacting relation, straps 108 are welded to the member 90 20 and formed to overlap the upper edge of the plate 100 and the vertical flanges of the ear members 104, which have some sliding motion relative to the strap 108 when pivoting takes place about the axis of the tube 96.

Direct forward thrusts are transmitted from the blade structure to the intermediate mounting assembly through the coacting surfaces of the plates 92 and 100. These are broad, flat surfaces, little subject to wear and deformation by over-stress.

For a number of reasons it is desirable to have the scraper or pusher blade located as close to the front of the tractor as is practically possible. The most obvious reason is that when the 35 blade is in angling position, to divert earth toward one side of the path of movement of the tractor, the greater the distance of the blade from the tractor, the greater is the tendency to throw the tractor off of the desired line of movement, particularly with Caterpillar type tractors. This increases the difficulty of operation and increases wear on the steering mechanism of the tractor.

Hence I believe that my construction which 45 allows a very close coupled mounting of the blade by reason of the thinness of the central portion 20 of the main frame has very real advantages in practice. Because the height, or vertical depth, of the frame is increased in the center portion 50 I do not sacrifice in strength or ruggedness by making the frame thinner from front to back in this part as the total cross sectional area of the metal of the frame at both ends of the portion 18 are substantially the same.

Furthermore, the structure makes a protective apron such as 46 both a functional and feasible part of the frame. Though progressively varying in cross sectional shape, the angular portion 18 connects smoothly with the thin central portion 20 but as can be seen from the plan view of Figure 2, the generally triangular shape has a rather wide base on the line joining the corners 28 and 30 so that the forces exerted by the angular members 18 are transmitted to the side members 16 65 without setting up undue stresses on the lines where the portions 18 join the portions 16.

A frame of this type also must withstand forces tending to distort it from its rectangular form, that is, the side thrusts occurring particularly 70 when the blade is in angling position, and also when there is a direct thrust against the blade when adjusted for bulldozing operations tending to spread or distort the side members from parallel with the longitudinal axis of the tractor. 75

The connection of the angular portions 18 to the side portions 16 wherein the plane dimensions, i. e., horizontal dimensions as from corner 28 to corner 30 are relatively great give the strength desired to overcome such distorting forces.

In the structure detailed in Figure 3 I have provided swivel means which permits a large surface of engagement by the swiveling members for transmitting the direction thrusts. This engagement occurs principally on the line between the plates 92 and 100. The area is so extensive that very little wear occurs because the forces are distributed thereover and the very great thrust forces are not exerted directly through the pivot or swivel means proper. For the swivel means itself the use of the tube and collar arrangement give also a relatively large surface of engagement in a structure which can be made from regular mill shapes assembled by welding without any expensive machine operations.

Some changes may be made in the construction and arrangement of the parts of my device without departing from the real spirit and purpose of my invention, and it is my intention to cover by my claims, any modified forms of structure or use of mechanical equivalents, which may be reasonably included within their scope.

I claim as my invention:

1. A thrust frame for mounting an earth moving blade on a tractor comprising side arms and a cross member, said cross member comprising forwardly converging portions of tubular cross section, such cross section progressing from a shape relatively wide horizontally and narrow vertically at said side arms to a shape relatively wide vertically and narrow horizontally at the earth moving blade, and swivel means for mounting said blade on said thrust frame comprising a perforated thrust plate adjacent the back of the blade, a tubular extension from the blade through the perforation of said thrust plate, a collar rotatable on said tubular extension and welded to said thrust plate, angle-shaped clips each having one leg welded in said tubular extension and its other leg extending across the edge of the collar to prevent removal of the collar from the tubular extension, and means for mounting said thrust plate and collar on said thrust frame.

2. Means for mounting an earth moving blade on a tractor comprising a U-shaped frame, and swivel means for mounting the blade on said U-shaped frame comprising a perforated thrust plate against the back of the blade, a tubular extension from the blade through the perforation of said thrust plate, a collar rotatable on said tubular extension and connected to said thrust plate, angle-shaped clips each having one leg welded in said tubular extension and its other leg extending across the edge of the collar to prevent removal of the collar from the tubular extension, and means for mounting said thrust plate and collar on said U-shaped frame.

3. Means for mounting an earth moving blade on a tractor comprising a U-shaped frame, and swivel means for mounting said blade on said U-shaped frame comprising a perforated thrust plate against the back of the blade, a tubular extension from the blade through the perforation of said thrust plate, a collar rotatable on said tubular extension and welded to said thrust

plate, retainer means on said extension engageable with said collar, and means for mounting said thrust plate and collar on said U-shaped frame for pivoting about a vertical axis with respect to said frame.

4. In an earth moving device, a U-shaped frame adapted for attachment to a tractor, an earth moving blade supported by said frame at the front end thereof for earth moving operations upon being propelled by said tractor, and swivel means for mounting said blade on said U-shaped frame comprising a perforated thrust plate against the back of the blade, a tubular extension from the blade through the perforation of said thrust plate, a collar welded to said thrust plate, angle-shaped clips each having one leg welded in said tubular extension and its other leg extending across the edge of the collar to prevent removal of the collar from the tubular extension, and means for mounting said thrust plate and collar on said U-shaped frame.

5. In an earth moving device, a yoke-shaped frame adapted for attachment to a tractor, an earth moving element supported by said frame at the front end of the tractor for earth moving operations upon forward movement of the tractor and universal swivel means for mounting said earth moving element on said frame comprising a perforated thrust plate against the back of the element, a tubular extension from the element through the perforation of said thrust plate, a collar welded to said thrust plate and rotatable on said tubular extension, means to prevent removal of said collar from said tubular extension and means for mounting said thrust plate and collar on said yoke-shaped frame, said means permitting said thrust plate to pivot about a vertical axis with respect to said frame.

6. Means for universal swivel mounting of an earth moving blade on a tractor thrust frame comprising a cylindrical member fixed to and projecting rearwardly from said blade, a thrust plate bearing against the rear of said blade, a perforation in said plate, said cylindrical member extending through said perforation, a collar fixed to said plate and surrounding said perforation, retainer means on said cylindrical member extending over said collar, mounting ears on said thrust plate, a king pin extending through said mounting ears, and means on said thrust frame for supporting said king pin whereby said blade and said plate are rotatable about said king pin with respect to said frame.

7. A thrust frame for mounting an earth moving blade on a tractor, comprising a U-shaped frame, and universal swivel means for mounting said blade on said U-shaped frame comprising a perforated thrust plate against the back of the blade, a tubular extension from the blade through the perforation of said thrust plate, a collar welded to said plate around said perforation, means adapted to retain said extension within said collar, said blade and said extension being rotatable about a horizontal axis with reference to said plate and said collar, a king pin, means on said plate for engaging said king pin, and means on said frame for supporting said king pin, said blade and said plate being rotatable with reference to said frame about said king pin.

ELLSWORTH W. AUSTIN.
